(57) **CLAIM**

The ornamental design for a table frame, as shown and described.

DESCRIPTION

FIG. 1 is a front-right-top perspective view of the table frame showing my new design;

FIG. 2 is a front elevational view thereof;

FIG. 3 is a rear front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof;

FIG. 9 is a portion of FIG. 1 enlarged for magnification purposes;

FIG. 10 is a portion of FIG. 1 enlarged for magnification purposes;

FIG. 11 is a front-right-top perspective, exploded view thereof; and,

FIG. 12 is a reference view thereof, showing the table frame in use.

The dot dash dot lines immediately adjacent to the shaded areas represent bounds of the claimed design. The broken line showing of the table seen in FIG. 12 is directed to environment while all other broken lines included for the purpose of illustrating portions of the table frame; all of the broken lines form no part of the claimed design.
